Des. 203,681
Patented Feb. 8, 1966

203,681

TRIPLE DRESSER

Bert J. Klein and Andre Bus, Altavista, and John B. Thorn, Lynchburg, Va.

Filed Apr. 19, 1965, Ser. No. 84,850

Term of patent 14 years

(Cl. D33—6)

The end of the article not shown is like the end shown while the back of the article is plain and unornamented.

We claim:

The ornamental design for a triple dresser, as shown and described.
